UNITED STATES PATENT OFFICE.

CHARLES H. ANDERSON, OF CINCINNATI, OHIO.

COMBINED FLOOR AND ELECTRIC-CONDUIT SYSTEM FOR STEEL CARS.

1,197,094.

Specification of Letters Patent.

Patented Sept. 5, 1916.

Original application filed June 18, 1914, Serial No. 845,894. Patent No. 1,147,999. Divided and this application filed January 27, 1915. Serial No. 4,674.

To all whom it may concern:

Be it known that I, CHARLES H. ANDERSON, a citizen of the United States, and a resident of Cincinnati, in the county of 5 Hamilton and State of Ohio, have invented certain new and useful Improvements in Combined Floor and Electric-Conduit Systems for Steel Cars; and I do hereby declare the following to be a full, clear, and 10 exact description of the invention, such as will enable others skilled in the art to which it appertains to make and use the same.

My invention relates to an improvement 15 in combined floor and electric conduit system for steel cars, and is a division of application on which Patent No. 1,147,999 was granted to me July 27, 1915.

The usual method of installing the electric wiring in steel and other cars, is by the use of enameled iron pipe secured to the car floor by clips. The complicated systems of automatic control now in use, necessitates the extensive use of this iron pipe, which 25 adds materially to the weight without adding strength to the car body. The cars now in use, carry from three hundred (300) to a thousand (1,000) pounds of this material which is difficult and expensive to install, 30 and in many instances necessitates raising the entire car body in order to pass the pipes over or above the motors.

The object of my invention is to obviate the disadvantages of the iron conduit system above referred to, and to so construct the floor of the car that the conduits for the conductors strengthen the floor throughout the length of the car body.

With this and other objects in view my 40 invention consists in the parts and combination of parts and in the details of construction as will be more fully explained and pointed out in the claims.

In the accompanying drawings, Figure 1 45 is a view in plan of a car floor embodying my invention; Fig. 2 is a view in side elevation of same, and also showing the motor leads, and Fig. 3 is an enlarged view in transverse section through a portion of the floor.

The floor 1 of the car consists of steel plates, continuous from side to side. Riveted, bolted or otherwise secured to the top of the floor plates 1, is a steel plate 2, bent 50 or pressed into the fluted or corrugated

form as shown, so as to provide a series of chambers or conduits 3 extending from end to end of the car. These channels or conduits are adapted to receive the electric wires 4, the wires entering and leaving said channels or conduits 3 through openings 5 in the plates 1. Secured to the lower face of the floor plates are the transverse steel boxes 6 which close the openings 5 in the floor, and communicating with said boxes 6, are the conduits 6^a which protect and carry the laterally extending wires 4 to the apparatus under the frame of the car, with which the said wires are connected. Those wires emerging from boxes directly over the 70 apparatus to which they are connected need not be protected by conduits.

Located between the floor plates 1 and the pressed steel conduit section 2, is a sheet 7 of insulating material, and above the conduit section 2 and resting on same, is a strip 8 of insulating material, which covers and protects said section through the width and length of the latter. The U-shaped grooves or spaces between the 80 conduits of the section 2 are filled with asbestos cement 9, or other suitable insulating material, and the two side edges of the conduit section are bounded by and held in place by the strips 10, of wood or other 85 material, which are secured to the floor plates 1 by bolts passing through the strips, edges of the conduit sections, insulating sheet 7 and the floor plates. At the side edges of the floor, next to the side plating 90 11, are wood strips 12 secured to the floor frame by bolts 13.

Located intermediate the strips 12 and 10, at each side of the conduit section 2 is a filling of cork or other suitable material 95 9^a and a binder, which not only insulates the floor but deadens the sound and prevents the floor plates from vibrating.

The tops of strips 8, 12 and 10 over the 100 conduit sections, and the filler intermediate the strips are all in the same horizontal plane, and are all covered by canvas 14, which forms the base for a covering of battleship linoleum, agasote or other material 105 15 that will stand the excessive wear to which a car floor is subjected.

With a car floor thus constructed, the plates 1 which form the foundation may be comparatively light, and not sufficiently stiff between cross beams, to hold the passenger 110

load. These plates 1, are however, stiffened by the conduit section 2, which as before explained is located at the longitudinal center of the car and extends throughout the 5 length of the latter, and forms in effect a center sill for the car floor, and by filling the upper grooves in the conduit section with an insulating material, and covering the floor plates at the sides with cork cemented together and held in place by canvas, the whole being covered with linoleum, I secure effective insulation against heat and cold, and thorough protection of the electric wires.

15 The conduits or channels for the electric wires are enameled on the inside so as to resist any flash that might occur from the burning out of a wire. The motor leads which extend laterally after passing 20 through the floor plates will be carried by the boxes 6 and conduits 6^a direct to their positions above the motors, and by locating the conduits above the floor plates, the leads to the end motors may cross the bolsters 25 without interference. Again with my construction the under side of the car floor, instead of being a net work of pipes held in place by clips, is a smooth surface broken only by the boxes 6, that may be readily 30 painted and kept in proper condition.

It is evident that many slight changes might be resorted to in the relative arrangement of parts shown and described without departing from the spirit and scope of my

invention. Hence I would have it understood that I do not wish to confine myself to the exact construction and arrangement of parts shown and described but,

Having fully described my invention what I claim as new and desire to secure 40 by Letters Patent, is:—

1. A car floor composed of metal plates, and a fluted metal section secured to the upper face of said plates and forming conduits extending lengthwise the car, the said 45 plates having openings communicating with said conduits and boxes secured to the lower face of the floor plates and covering said openings and for protecting and carrying 50 the wires.

2. A car floor composed of metal plates and a fluted metal section secured to the upper face of said plates and forming a series of conduits extending lengthwise the car, the said floor plate having openings 55 communicating with said conduits, boxes secured to the lower face of the floor plate and covering said opening and conduits leading from the boxes for protecting and carrying 60 the wires to the desired points.

In testimony whereof I have signed this specification in the presence of two subscribing witnesses.

CHARLES H. ANDERSON.
